UNITED STATES PATENT OFFICE.

JOSEPH H. HANNON, OF NATHAN, MICHIGAN.

EXTENSION-BED.

No. 811,216.

Specification of Letters Patent.

Patented Jan. 30, 1906.

Application filed June 21, 1905. Serial No. 266,308.

To all whom it may concern:

Be it known that I, JOSEPH H. HANNON, a citizen of the United States, residing at Nathan, in the county of Menominee, State of Michigan, have invented certain new and useful Improvements in Extension-Beds; and I do hereby declare the following to be a full, clear, and exact description of the invention, such as will enable others skilled in the art to 10 which it appertains to make and use the same.

This invention relates to bedsteads.

One object of the invention is to provide a bedstead embodying such characteristics that it may be readily converted into a single 15 or double bedstead.

Another object of the invention resides in the provision of an exceedingly simple, inexpensive, durable, and efficient bedstead of such character that an iron or other bedstead 20 may be readily converted from a double into a single bedstead.

With these and other objects in view the present invention consists in the combination and arrangement of parts, as will be 25 hereinafter more fully described, shown in the accompanying drawings, and more particularly pointed out in the appended claim, it being understood that changes in the form, proportion, size, and minor details may be 30 made within the scope of the claim without departing from the spirit or sacrificing any of the advantages of the present invention.

In the drawings, Figure 1 is a top plan view. Fig. 2 is an elevation of a head-post, 35 illustrating the single bedstead.

Referring now more particularly to the accompanying drawings, the reference characters 1 and 2 designate the head-posts of the bedstead, the post 1 having upper and lower 40 horizontal rods 3 and 4 and the post 2 having upper and lower horizontal rods 5 and 6, respectively, the free ends of the rods 3, 4, 5, and 6 being screw-threaded for a purpose presently explained.

The reference character 7 designates a 45 headboard-section consisting of vertical rails 8, which are connected at their upper ends to an oval-shaped or horizontal loop member 9, having screw-threaded studs 10 and 11 at its 50 ends, there being a horizontal rod 12 connected to the lower end of the vertical bars 8 and

extending upon both sides thereof with screw-threaded extremities. The screw-threaded studs 10 and 11 of the loop member 9 are designed to aline with the horizontal rods 3 and 5 of the headboard and are held in alinement by means of suitable collars 13 and 14, the said collars being interiorly screw-threaded for engagement with the screw-threads of the respective studs and bars 3 and 5 of the head 60 of the bedstead, it being understood that the collars have right and left threads. The lower horizontal bar 12 is in alinement with the short rods 4 and 6 and is held in alinement therewith by means of the collars 15 and 16, which latter have right and left threads for proper engagement with the right and left threads of the short horizontal bar 12 and the alining horizontal bars 4 and 6. Connecting the horizontal members 3 and 4 70 and 5 and 6 are vertical rods 17, which aline with the aforesaid vertical rods 8.

A double bedstead has been described, and in order to convert the same into a single bedstead it is simply necessary to remove the 75 section 7, which may be done by unscrewing the collars 13, 14, 15, and 16 and connecting the respective ends of the bars 3 and 5 and 4 and 6 by means of any of the collars 13, 14, 15, or 16.

It will be understood that the foot of the bedstead is formed in the same manner as is the head thereof, and it is to be still further understood that the bedstead may be formed of solid, tubular, or other form and character 85 of material.

What is claimed is—

A convertible bedstead comprising oppositely-disposed posts, upper and lower rods connected to each post, said rods having their 90 extremities screw-threaded, a section having a horizontal bar at its lower end screw-threaded at its extremities, and a loop member at its upper end, provided with screw-threaded projections at its ends, the horizontal 95 bar of the said section being adapted for alinement with the lower short rods of the respective posts and the said projections being arranged for alinement with the upper rods of the respective posts, collars arranged for 100 screw-threaded engagement with the upper horizontal rods and the corresponding pro-

jections of the said loop of said section, and
collars arranged for screw-threaded engage-
ment with the lower horizontal rods of the re-
spective posts and the horizontal rod of said
5 section, whereby the latter may be discon-
nected from the head and foot of the bed-
stead.

In testimony whereof I affix my signature
in presence of two witnesses.

JOSEPH H. HANNON.
